(57) **CLAIM**

The ornamental design for an article of seating furniture, as shown and described.

DESCRIPTION

FIG. 1 is an isometric view of an article of seating furniture incorporating my new design, wherein the portions in phantom illustrate indeterminate length and also illustrate environment and form no part of the claimed design;

FIG. 2 is a front elevation view thereof;

FIG. 3 is a top plan view thereof;

FIG. 4 is a right side elevation view thereof, wherein the left side elevation view is a mirror image;

FIG. 5 is a rear elevation view thereof;

FIG. 6 is an isometric view similar to FIG. 1, showing another embodiment of an article of seating furniture incorporating my new design, wherein the top plan view, side elevation views and rear elevation view are the same as shown with respect to the embodiment of FIGS. 1-5;

FIG. 7 is a front elevation view thereof;

FIG. 8 is an isometric view showing an article of seating furniture as in FIG. 1 converted to a bed configuration;

FIG. 9 is a front elevation view thereof;

FIG. 10 is a top plan view thereof;

FIG. 11 is a right side elevation view thereof, wherein the left side elevation view is a mirror image;

FIG. 12 is a rear elevation view thereof;

FIG. 13 is an isometric view showing an article of seating furniture as in FIG. 6 converted to a bed configuration, wherein the side elevation views are the same as illustrated with respect to the embodiment of FIGS. 8-12;

FIG. 14 is a front elevation view thereof; and,

FIG. 15 is a rear elevation view thereof.
